(57) **CLAIM**

The ornamental design for a display screen with graphical user interface, thereof as shown and described.

DESCRIPTION

FIG. 1 is a perspective view of a display screen with graphical user interface thereof showing our new design.

FIG. 2 is a perspective view of a display screen with graphical user interface thereof showing our new design.

FIG. 3 is a perspective view of a display screen with graphical user interface thereof showing our new design; and,

FIG. 4 is a perspective view of a display screen with graphical user interface thereof showing our new design.

The broken line drawings of the screen display in the Figures form no part of the claimed design. The text and other elements shown in dotted lines are for illustrative purposes only and form no part of the claimed design.

The appearance of the transitional user interface sequentially transitions between the images shown in FIG. 1-4. The process of period in which one image transitions to another forms no part of the claimed design.
